SPRING ACTUATED SLIDE SNAP HOOK

Filed Nov. 22, 1948

UNITED STATES PATENT OFFICE

2,592,843

SPRING ACTUATED SLIDE SNAP HOOK

Boley A. Andrews, Kansas City, Kans., assignor,
by mesne assignments, to The Vendo Company,
Kansas City, Mo., a corporation of Missouri

Application November 22, 1948; Serial No. 61,475

1. Claim. (Cl. 24—239)

1

This invention relates to garage door openers and particularly of the type wherein the door is movable from a closed position to an overhead position in a substantially horizontal plane through the medium of an electric motor or like prime mover having connection with the door through an interconnecting rectilinearly movable follower block.

It is the most important object of this invention to provide a novel coupling or hitch for joining an overhead garage door with a follower block of the above-mentioned character, said coupling including an interlocking device on at least one end thereof that may be easily and quickly disconnected regardless of the position of the door and irrespective of the weight that is on the coupling at the time such disconnection takes place.

It is common knowledge in the field of garage door mechanisms of the kind above set forth that oftentimes operational failures of the automatic door controlling assembly itself necessitates disconnecting of the door for manual opening and closing thereof while the control mechanism is being repaired and out of order.

Coupling means heretofore provided between the door itself and the control means therefor have been so complicated that a quick and easy disconnection is not possible. This problem is enhanced when those not particularly skilled mechanically are faced with the problem of a jammed door and by those who do not have the physical strength necessary to make such disconnection.

It is, accordingly, one of the most important objects of the present invention to provide a coupling that includes an elongated link provided with a hook on one end thereof for receiving a pin, said link, also, having a latch member slidably mounted thereon for movement to and from a position closing the mouth of the hook and thereby releasably clamping the pin in place and interlocked with the link.

A further object of the present invention is to provide a coupling of the above-mentioned character having an extensible linkage provided with latching means on both ends thereof of identical character, to the end that, when disconnection becomes necessary, that end of the linkage most conveniently accessible can be manipulated with ease and dispatch.

Other objects of the present invention relate to details of construction that will become apparent as the following specification progresses.

2

reference being had to the accompanying drawing, wherein:

Fig. 1 is a side elevational view of a releasable hitch made in accordance with the present invention, showing the same operably mounted upon a door and joined with actuating mechanism for such door.

Fig. 2 is an enlarged, side elevational view of the coupling, per se, parts being broken away and in section to reveal details of construction.

Fig. 3 is a cross sectional view taken on irregular line III—III of Fig. 2, looking in the direction of the arrows.

Fig. 4 is a fragmentary, side elevational view showing one end of the coupling with the latch thereof in a released condition; and,

Fig. 5 is a transverse, cross sectional view taken on line V—V of Fig. 2, looking in the direction of the arrows.

20 The garage door opening mechanism shown schematically in Fig. 1 of the drawing forms the subject matter of my copending application No. 61,473, filed November 22, 1948, entitled "Motor Actuated Door Operator"; and, while the same forms no part of the present invention, the broad operation thereof is as follows:

The ceiling of a garage is illustrated by the numeral 10 and the front wall of the garage by the numeral 12. Wall 12 is provided with an access opening 14 that is closed by a door 16 that includes a plurality of articulated sections mounted between a pair of U-shaped tracks, one of which is illustrated in Fig. 1 of the drawing and designated by the numeral 18.

35 A motor (not shown) within a housing 20 is suspended from the ceiling 10 near one end thereof opposite to front wall 12, said motor having operable connection with a follower rectilinearly mounted within a track 22 depending from ceiling 10 and extending longitudinally of the garage. Said follower has a bracket 24 secured to the bottom thereof by means of bolts or the like passing through openings 26 of bracket 24.

40 This bracket 24 is more clearly illustrated in Figs. 2 and 3 of the drawing and is U-shaped in cross section to present a pair of spaced legs 28 that are interconnected by removable cross pin 30 held in place by key 32. It is apparent that the bight of bracket 24 has the bolt holes 26 formed therein.

45 A similar bracket 34 is mounted upon the door 16 by bolts or the like 36, said bracket 34, also, being provided with a cross pin 38 interconnecting the legs thereof. The coupling or hitch 55 forming the subject matter of this invention and

about to be described is designed to span the distance between the pins 30 and 38 of brackets 28 and 34, respectively, said coupling being broadly designated by the numeral 40.

Coupling 40 includes a pair of identical, elongated links 42 and 44 having their proximal ends overlapped and joined by a pair of bolts 46. The links 42 and 44 are provided with aligned, elongated slots 48 for receiving the bolts 46; and intermeshing, transverse teeth 50 on the proximal faces of links 42 and 44 hold the same interconnected when the bolts 46 are tightened down.

It is thus far apparent that the interconnecting bar formed by links 42 and 44 is extensible through loosening of bolts 46. The outermost, free ends of links 42 and 44 and the latching means for interconnecting the same to the respective pin 30 or 38 are the same; and, therefore, such latching means with respect to link 42 only will be described.

The outermost free end of link 42 is provided with a hook defining an elongated notch or recess 52 extending inwardly from one of the longitudinal edges of link 42. The width of this notch 52 is substantially the same as the diameter of pin 30, to the end that link 42 may be looped about the pin 30 in the manner illustrated in Figs. 2 and 4. A latching member 54 is disposed in partial embracing relationship to the link 42 adjacent that end thereof having notch 52 formed therein, said latching member 54 being U-shaped in cross section, as illustrated in Fig. 5 of the drawing.

Thus, when latch 54 slides upon the link 42, the bight thereof frictionally engages the longitudinal edge of link 42 having notch 52 formed therein. The legs of the latch 54 overlap and slide upon the opposed side walls of link 42.

The two side walls of latch 54 are provided with aligned, elongated, longitudinally-extending slots 56 intermediate the ends thereof for receiving a transverse pin 58 mounted in the link 42. One end of the pin 58 extends outwardly beyond the outermost face of the latch 54 for receiving one end of a spring 60. The opposite end of spring 60 is secured to one of a pair of outturned flanges 62 on the member 54. These flanges 62 are disposed on that end of the member 54 remote from the notch 52 and are substantially perpendicular to the sides of member 54.

That end of the member 54 opposite to the outturned flanges 62 has the side walls thereof provided with aligned, inwardly-extending, elongated recesses or notches 64. The longitudinal axes of the notches 64 are disposed on a line substantially midway between the top and bottom of the respective walls of member 54 and in alignment with the longitudinal axes of such walls.

Thus, as is apparent in Figs. 2 and 4 of the drawing, the longitudinal axes of the two notches 64 are substantially perpendicular to the longitudinal axis of the notch 52 formed in link 42. When the latch member 54 is in the operative position of Fig. 2 of the drawing, the pin 30 is not only disposed within the notch 52 of link 42 but is embraced by the two notches 64 of the side walls of U-shaped member 54.

A portion of the bight of latch 54 overlies and closes entirely the mouth of notch 52. A portion of the side walls of member 54 between the bight thereof and notches 64 overlaps the link 42 on both sides thereof and on both sides of the notch 62. By the same token, the mouths of the notches 64 are closed by the end of link 42 that is disposed outwardly from the notch 52.

The spring 60 yieldably holds the latch member 54 biased in the operating position shown in Fig. 2 of the drawing and, when latch 54 is in said position, that end of the slots 56 proximal to the flanges 62 bears against the pin 58 and limits the extent of outward movement of latch 54 on link 42.

Releasing of the coupling is simple and accomplished by merely grasping the flanges 62 and exerting an inward pull to the member 54 with respect to link 42. Such movement of the member 54 against the action of spring 60 will position the member 54, as illustrated in Fig. 4 of the drawing, where link 42 is free to drop from its position embracing the pin 30.

Doors of the character illustrated in Fig. 1 are usually provided with counterbalancing means and at no time will the pressure upon the coupling 40 be so great that the same cannot be easily swung from the operative position when either or both of the two latching means 54 is moved inwardly on the respective links 42 and 44. The coupling 40 is devoid of all complicated interconnecting means requiring the use of tools, particularly those of a special nature, in order to effect disconnection.

Conversely, after the door actuating mechanism has been repaired, replacement of the coupling 40 is just as simple through a reverse procedure.

The simplicity of the coupling just described renders the same capable of many changes and modifications, and the advantages emanating from its use in many other fields differing from that herein chosen for illustration is apparent. Accordingly, such changes as fairly come within the scope of the appended claim are contemplated hereby.

Having thus described my invention, what I claim as new and desire to secure by Letters Patent is:

A rod-receiving coupling comprising an elongated, flat link having a U-shaped recess formed in one longitudinal edge thereof; an elongated, U-shaped body mounted on the link and having a bight slidably engaging said one longitudinal edge of the link and a pair of spaced, parallel side walls, slidably engaging corresponding sides of the link and integral with said bight, said side walls each having an elongated, longitudinally extending slot formed therein and a U-shaped notch in one end thereof proximal to the recess, said notches each having a pair of straight edges disposed in converging relationship as the innermost ends thereof are approached; an outturned, finger-receiving flange on each side wall of the body adjacent the opposite end thereof; a transverse guide pin affixed to the link and extending through said slots of the side walls for holding said bight in engagement with said edge of the link; and a spring having one end thereof attached to said pin and the opposite end thereof attached to one of said flanges for pulling the flanges toward the pin and thereby yieldably holding the body at one end of its path of travel on the link with the notches registering with said recess, with the mouth of the recess closed by a portion of said side walls and said bight and with the mouths of the notches closed by a portion of the link, whereby to receive said rod in engagement with the notches and the recess at the bights thereof, said last mentioned bights being arcuate.

BOLEY A. ANDREWS.
